UNITED STATES PATENT OFFICE.

JOHN L. BATES, OF BROOKLYN, NEW YORK, ASSIGNOR OF ONE-HALF TO
HOMER BROOKE, OF JERSEY CITY, NEW JERSEY.

COLLAPSING SATCHEL.

SPECIFICATION forming part of Letters Patent No. 476,862, dated June 14, 1892.

Application filed January 13, 1892. Serial No. 417,906. (No model.)

To all whom it may concern:

Be it known that I, JOHN L. BATES, a citizen of the United States, residing in the city of Brooklyn, county of Kings, State of New York, 5 have invented certain new and useful Improvements in Collapsing Satchels, of which the following is a specification.

My invention relates to the construction of hand bags or satchels with the view of adapting the same to collapse and also to fold for convenience of stowage and carriage when not in use; and to this end it consists in certain novel arrangement of jointed ribs or stays upon a satchel-body of collapsible material, as hereinafter more fully described with reference to the accompanying drawings, in which—

Figure I represents a side view of a satchel embodying the invention. Fig. II represents 20 a central longitudinal section thereof. Fig. III represents a cross-section thereof in the plane of the line $x x$, Fig. II. Figs. IV and V represent detail views of rib-joints.

Similar letters of reference indicate similar 25 parts.

The letter A indicates the satchel-body, which is of a flexible material capable of being crushed or collapsed and usually in one piece, folded so as to present two sides A' A². 30 Each of the sections A' A² is usually furnished on its upper part with a strap loop A³, forming a handle, and also with suitable fastenings.

B indicates the ribs of the satchel-body and 35 C the joints or articulations of the ribs. Said ribs B are usually of wire and extend longitudinally of the body A, they being fitted in suitable pockets D thereof, and each of the ribs is curved in such a manner that by the series of ribs said body under normal conditions assumes and preserves an approximately-oval shape in both directions; but it is evident that the shape of the body may be varied. The pockets D, containing the ribs 40 B, may be formed between the cover and lining of the satchel-body, as by rows of stitching e, extending in the required planes, and the effect of these pockets is to retain the ribs in the desired positions on the body, also to 45 conceal the ribs, and to protect the contents of the satchel therefrom.

The joints C of the satchel-shaping ribs are intermediate of the ends thereof and at points coincident with each other relatively to the transverse plane of the satchel-body, said 55 joints being in the example shown at about the mid-length of the ribs, thereby dividing each of the latter into two equal parts or sections, as shown. The location of the ribs joints C, however, may be varied, and, if desired, each of the ribs may be joined at two or more places.

Each of the rib-joints C is formed by means of a link, which is interlaced with eyes or loops C' on the inner ends of the rib-sections, 60 the effect of this link being to impart a superior flexibility to the respective joints; but a good result may also be obtained by interlacing said inner end eyes C' of the rib-sections or otherwise constructing the joints 65 without the use of the link. Said link, which is the part marked C, may be of wire and either round, as shown in Fig. II, or oblong, as shown in Fig. IV, or it may be composed of a strip of leather or other similar material, 70 as shown in Fig. V.

On the outer ends of each of the ribs B are eyes or loops B', whereby the ribs are interlaced with rings G, lying transversely to the satchel at its opposite ends and within the 80 body. Each of these rings G is common to the series of ribs B, and the purpose thereof is to form supports for the outer ends of the ribs and without permanently connecting the latter to the satchel-body, thereby simplifying 85 the construction of the article, the support thus afforded being also very effective, due to its uniform distribution. In order to permit the required adjustment of the rib ends on the rings G, the ends of the pockets D 90 should be left open and in some cases the rings G may be elastic.

It will be apparent that by the jointed ribs B the satchel-body A is adapted to be folded on itself from the opposite ends thereof, while 95 by the arrangement of the ribs in longitudinal planes they also permit the body to be collapsed crosswise, so that the article may be brought into the smallest possible compass, the ribs at the same time keeping the body 100 in shape when it is unfolded for use. One of the ribs B is located at the upper edge of

each of the sections A' A² of the satchel-body, as shown, and thus serves to determine and preserve the shape of the mouth of the article.

5 What I claim as new, and desire to secure by Letters Patent, is—

1. A satchel having longitudinal shaping-ribs which are jointed intermediate of the ends at points coincident with each other, in combination with a satchel-body of flexible and collapsible material, having pockets containing said ribs and supports for the outer ends of the ribs, substantially as and for the purpose described.

2. A satchel having a body of flexible and collapsible material and longitudinal shaping-ribs which are jointed intermediate of the ends at points coincident with each other, in combination with the transverse supporting-rings at the opposite ends of the body, having the outer ends of the series of ribs interlaced therewith, substantially as and for the purpose described.

JOHN L. BATES.
